UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

METHOD AND APPARATUS FOR TREATING SHOES.

Application filed May 27, 1924. Serial No. 716,169.

To all whom it may concern:

Be it known that I, FREDERICK M. FURBER, a citizen of the United States, residing at Revere, in the county of Suffolk and Commonwealth of Massachusetts, have invented 5 certain Improvements in Methods of and Apparatus for Treating Shoes, of which the following description, in connection with the accompanying drawings, is a specification, 10 like reference characters on the drawings indicating like parts in the several figures.

This invention relates to methods of and apparatus for treating shoes, and more particularly to the softening of the marginal 15 portion of the upper and the stiffening members at the toe-end and heel-end of a shoe preparatory to the lasting operation.

It has become almost universal practice 20 to soften the toe-end of a shoe by means of hot moist vapor to facilitate shaping the upper and the stiffening member to conform to the toe of the last. In some cases the hot moist vapor for this purpose is obtained from steam generated at a remote 25 source and conveyed under pressure through piping by which it is emitted adjacent to the treating locality, while in other cases the vapor is generated at atmospheric pressure adjacent to the treating locality by a heater 30 to which a liquid, usually water, is supplied under suitable regulation.

It has been proposed to soften the materials at the heel-end of the shoe while the materials at the toe-end are being softened, 35 but the simultaneous softening of both ends, according to prior conceptions, has been confined to the above-mentioned principle of utilizing steam generated under pressure at a remote source and emitted adjacent to the 40 treating localities. The last-named principle involves difficulties in the regulation of the volume and temperature of the vapor supplied to the work, and the simultaneous softening of both ends of a shoe has not acquired the extent of use anticipated.

In view of the conditions above explained, 45 an object of the present invention is to provide improvements in methods of simultaneously treating the toe-end and the heel-end of a shoe, while another object is to provide improved apparatus for practicing such treatment to satisfy the requirements of those shoe manufacturers who would prefer to soften both ends simultaneously if

satisfactory means for doing so were 55 available.

Referring first to the method aspect of the present invention, considered from one viewpoint, the invention consists in supplying radiant heat to the toe-end and to the 60 heel-end of a shoe simultaneously, and at the same time generating and furnishing hot moist vapor at atmospheric pressure adjacent to each of the two ends individually.

A novel feature, stated in terms of apparatus, consists in a combination comprising means for supporting a shoe, a heater arranged to supply radiant heat to the toe-end, a heater arranged to supply radiant heat to the heel-end, and means for supplying a liquid to each of said heaters individually to be converted into hot moist vapor at atmospheric pressure adjacent to the toe-end and heel-end respectively.

Another novel feature consists in the 75 above-described combination with the addition of individual controls for regulating the quantity of liquid supplied to each of the heaters individually so that the quantity of hot moist vapor supplied to the heel-end 80 may be regulated independently of the quantity supplied to the toe-end, and vice versa.

Still another novel feature consists in arranging the individual heaters so that they 85 may be relatively adjustable one toward and from the other according to the length of shoe to be treated thereby.

The invention also provides for individual regulation of the temperature of the vapor 90 and the radiant heat generated at each end of the shoe.

Other features of the invention are hereinafter described and claimed and illustrated by the accompanying drawings.

Referring to the drawings,

Fig. 1 is a side elevation, partly in section, of an apparatus embodying a preferred form of construction;

Fig. 2 is a front elevation, partly in section, of said apparatus; and

Fig. 3 is a wiring diagram of a preferred arrangement of electrical equipment for furnishing heat to the apparatus.

The upper portion of a supporting column 105 is represented at 10. A bracket 12 surrounding the column and fixed thereto by a set-screw 14 supports a water-reservoir 16 and

the treating apparatus, the latter being fastened to the bracket by screws 18.

The illustrated apparatus, which is designed to treat two shoes simultaneously, includes a cast iron housing 20. This housing takes the attaching screws 18 and is thermally insulated from the bracket 12 by a plate 22 of compressed asbestos. The housing is formed with a back wall 24, a bottom wall 26 and the end walls, but is open at the front to receive the toes of two shoes side by side and is provided with an adjustable top wall 28 by which the vertical dimension of the toe-receiving chamber may be regulated. For this purpose the top wall 28 is mounted on trunnions 30, 30, one of which is provided with a screw-thread and with a wing nut 32 to clamp the wall at any desired angle. The trunnions extend through the end walls of the housing 20, and when the wing nut is tightened it clamps the adjustable wall 28 against one of the end walls.

The lower part of the housing 20 is formed to provide a vapor chamber 34 under the bottom wall 26. The vapor for treating the toe portions of the shoes is generated in this chamber 34 and rises through holes 36 in the bottom wall 26. Sockets are formed in the lower part of the housing 20 to receive electric heating units 38. In the illustrative embodiment of the invention the housing is provided with three heating units 38, all of which are represented in Fig. 2. The sockets for their reception are closed at the front end but open at the rear end, and the electrical conductors for supplying the current to them are indicated at 40. The heat from the electric units 38 is sufficient to heat the entire housing 20 to a temperature that will furnish the necessary radiant heat to the shoe materials and convert the water in the chamber 34 into hot moist vapor. The water for this purpose is delivered into the chamber 34 by a pipe 42. A cup-shaped fitting 44 attached to the upper end of the pipe 42 receives the water from the reservoir 16 through a valve 46, and a gap between the valve and the fitting 44 is provided to enable the user to observe the rate at which the water is being supplied. Since the requirements for vapor are small it is usually sufficient to supply the water one drop at a time rather than to maintain a continuous stream, but a greater quantity may be supplied by giving the valve 46 its full opening.

The elements for supplying vapor to treat the heel ends of the shoes include a heat-radiating member 50, preferably of cast iron. This member is hollow to provide a vapor chamber 52 and it has sufficient lateral dimension (see Fig. 2) to underlie the heel parts of both shoes. Holes 54 are formed in the upper wall of the

member 50 to release the vapor under the heel parts. Water is supplied to the chamber 52 by a conduit including a flexible pipe 56, the receiving end of which is attached to a cup-shaped fitting 58. This fitting is affixed to the reservoir 16 and is provided with a sight-feed gap and with a valve 60 by which the water may be regulated to drip or flow in a continuous stream into the cup. The cast iron member 50 is also provided with a socket to receive an electric heating unit 62.

The member 50 is supported so that it may be adjusted toward and from the housing 20 according to the length of the shoes to be treated, and for this purpose it is attached to a bracket 64 having a horizontal slot 66 of a length great enough to provide for the desired range of sizes. A screw stud 68 extends through an ear 70 of the member 50 and through the slot 66 and is provided with a hand nut 72 by which the ear 70 may be clamped in various positions to the bracket 64. In Fig. 1 the member 50 is represented by broken lines in a position at the right-hand end of the slot 66 where it is as close as possible to the housing 20 to treat a shoe of the smallest size. The member 50 is also adjustable vertically, and for this purpose the ear 70 is provided with a vertical slot or notch 74 through which the stud 68 extends.

Although various provisions may be made for regulating the temperature of the housing 20 and the heat-radiating member 50 I prefer the means represented conventionally in Fig. 3. Current supply wires are indicated at 76 and individually controllable rheostats are indicated at 78 and 80. The rheostat 78 controls the heating units 38 which are connected in parallel, while the rheostat 80 controls the heating unit 62. A box 82 may be attached to the column 10 to enclose the rheostats and other parts necessary to complete the electrical equipment.

The toe-ends of the shoes are supported out of contact with the bottom wall 26 by screws 84 standing up from said wall and having large flat-heads to engage the insoles, but to accommodate a large range of sizes of shoes it is desirable to use a support for the heel-ends that may be adjusted according to the length of the shoes. Accordingly, the invention includes an improved adjustable work-support for this purpose. Referring to Fig. 2, a rod 86 bent to a U-shape, has sufficient horizontal dimension in its mid-portion to support two shoes side by side. The arms or end portions of this rod are inserted downwardly through holes extending transversely through a rock-shaft 88. This shaft is arranged to turn in bearings 90 in a bracket fastened to the front of the housing 20. One end of the rock-shaft is

- provided with a screw stem 92 and a hand nut 94. The rod 86 straddles the two bearings 90 and engages the outer end of each so that when the hand nut 94 is tightened it 6 acts through the rock-shaft 88 to draw one arm of the rod 86 against the left-hand bearing 90 while the hand nut forces the other arm of the rod against the other bearing 90. The hole for the latter arm is 10 slightly larger than the arm to provide clearance for this dual clamping action. The two arms are thus simultaneously clamped by the nut 94. This form of clamping means provides for both vertical and 15 horizontal adjustment of the work-engaging portion of the rod 86. For example, when the nut 94 is loose the arms of the rod 86 may slide up and down through the holes in the rock-shaft 88, and the rock-shaft may 20 turn about its axis to permit the work-engaging portion of the rod to be placed at various distances from the housing 20.
- Having thus described my invention, what I claim as new and desire to secure by 25 Letters Patent of the United States is:
1. That improvement in methods of treating shoes, which consists in supplying radiant heat to the toe-end and heel-end of a shoe simultaneously and at the same time generating individual supplies of hot moist vapor adjacent to said toe-end and heel-end respectively and furnishing said vapor to the shoe.
  2. That improvement in methods of treating shoes, which consists in generating individual supplies of heat adjacent to the toe-end and heel-end of a shoe simultaneously and at the same time generating individual supplies of hot moist vapor adjacent to said toe-end and heel-end respectively and furnishing said vapor to the shoe.
  3. That improvement in methods of treating shoes, which consists in supplying radiant heat to the toe-end and heel-end of a shoe simultaneously and at the same time delivering individual supplies of liquid to heated areas adjacent to the toe-end and heel-end respectively and furnishing the resultant hot moist vapor to the work.
  4. That improvement in methods of treating shoes, which consists in radiating heat upwardly under the toe-end and heel-end of a shoe and at the same time generating and furnishing individual supplies of hot moist vapor under said toe-end and heel-end.
  5. That improvement in methods of treating shoes, which consists in delivering individual supplies of water to points adjacent to the toe-end and heel-end, respectively, of a shoe, and at the same time evaporating the water at said points by heat and furnishing the resultant vapor to the work.
  6. That improvement in methods of treating shoes, which consists in delivering individual supplies of water at points under

and adjacent to the toe-end and heel-end, respectively, of a shoe, and at the same time generating heat at said points to evaporate the water and heat the work by upward radiation.

7. A shoe-treating apparatus comprising means for supporting a shoe, heating means arranged adjacent to the toe-end of the shoe, heating means arranged adjacent to the heel-end, and means for supplying liquid to each of said heating means individually to be converted into hot moist vapor.

8. A shoe-treating apparatus comprising means for supporting a shoe so that the under surface of the toe-end and the under surface of the heel-end will be exposed, heat radiating means arranged to underlie said toe-end, heat radiating means arranged to underlie said heel-end, and means for supplying liquid to each of said heat-radiating means individually to be converted into hot moist vapor.

9. A shoe-treating apparatus comprising means for supporting a shoe so that the under surface of the toe-end and the under surface of the heel-end will be exposed, two metallic heat-radiating members arranged to underlie said toe-end and heel-end respectively, and means for delivering individual supplies of water to said members so that it will flow on them and furnish hot moist vapor to the work.

10. A shoe-treating apparatus comprising means for supporting a shoe so that the under surface of the toe-end and the under surface of the heel-end will be exposed, heating means arranged to underlie said toe-end, heating means arranged to underlie said heel-end, said two heating means being relatively adjustable one toward and from the other, and means for supplying liquid to each of said heating means individually to be converted into hot moist vapor.

11. A shoe-treating apparatus comprising means for supporting a shoe so that the under surface of the toe-end and the under surface of the heel-end will be exposed, heating means arranged to underlie said toe-end, heating means arranged to underlie said heel-end, said supporting means and said heating means being relatively adjustable vertically to regulate the depth of space between the shoe and the heating means, and means for supplying liquid to each of said heating means individually to be converted into hot moist vapor.

12. A shoe-treating apparatus comprising means for supporting a shoe so that the under surface of the toe-end and the under surface of the heel-end will be exposed, heating means arranged to underlie said toe-end, heating means arranged to underlie said heel-end, a reservoir for liquid, and conduits communicating with each of said heating means individually for supplying liquid

from said reservoir to be converted into hot moist vapor.

13. A shoe-treating apparatus comprising means for supporting a shoe so that the under surface of the toe-end and the under surface of the heel-end will be exposed, heating means arranged to underlie said toe-end, heating means arranged to underlie said heel-end, a reservoir for liquid, and conduits

10 communicating with each of said heating

means individually for supplying liquid from said reservoir to be converted into hot moist vapor, one of said heating means being adjustable and the liquid-supplying conduit communicating therewith having compensating means to provide for such adjustment.

In testimony whereof I have signed my name to this specification.

FREDERICK M. FURBER.
